CLAIM

The ornamental design for a wipes container lid, as shown and described.

DESCRIPTION

FIG. 1 is a top, perspective view of a wipes container lid according to the new design;

FIG. 2 is a top plan view of the embodiment of FIG. 1; FIG. 3 is a bottom plan view of the embodiment of FIG. 1; FIG. 4 is a back elevation view of the embodiment of FIG. 1;

FIG. 5 is a front elevation view of the embodiment of FIG. 1;

FIG. 6 is a right side elevation view of the embodiment of FIG. 1;

FIG. 7 is a left side elevation view of the embodiment of FIG. 1;

FIG. 8 is a bottom, perspective view of the embodiment of FIG. 1; and,

FIG. 9 is a cross section view taken along the line shown in FIG. 3 of the embodiment of FIG. 1.

In the drawings, the evenly-spaced broken lines show portions of a wipes container lid that form no part of the claim; the dash-dot-dash lines represent boundaries of the claimed design and form no part thereof.
